CLAIM

The ornamental design for a sports goal having chain link, as shown and described.

DESCRIPTION

FIG. 1 is a perspective view of a sports goal having chain link;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view showing the sports goal separated from the chain link and the netting, for ease of illustration;

FIG. 9 is a front right perspective view showing the chain link separated from the sports goal and netting, for ease of illustration;

FIG. 10 is a front elevational view showing the chain link separated from the sports goal and netting, for ease of illustration;

FIG. 11 is a rear elevational view showing the chain link separated from the sports goal and netting, for ease of illustration;

FIG. 12 is a left side elevational showing the chain link separated from the sports goal and netting, for ease of illustration;

FIG. 13 is a right side elevational showing the chain link separated from the sports goal and netting, for ease of illustration;

FIG. 14 is a top plan view showing the chain link separated from the sports goal and netting, for ease of illustration; and, FIG. 15 is a bottom plan showing the chain link separated from the sports goal and netting, for ease of illustration.

The screw fixture openings, and netting shown in broken lines in FIGS. 1-8 are included for the purpose of illustrating the environment in which the sports goal having chain link design is used and form no part of the claimed design.

The nuts and bolt shown in broken lines in FIGS. 1-3, 7, and 9-15 are included for the purpose of illustrating the environment in which the sports goal having chain link design is used and form no part of the claimed design.
